Primary Examiner — Omeed Agilee(74) *Attorney, Agent, or Firm* — Fish & Richardson P.C.(57) **CLAIM**

The ornamental design for a slide holder, as shown and described.

DESCRIPTION

FIG. 1 is a perspective view of a slide holder showing my new design;

FIG. 2 is a front view thereof;

FIG. 3 is a back view thereof;

FIG. 4 is a right view thereof;

FIG. 5 is a left view thereof;

FIG. 6 is a top view thereof; and,

FIG. 7 is a bottom view thereof.

The broken lines in the figures represent portions of the slide holder that form no part of the claimed design.
